(57) **CLAIM**

The ornamental design for a magnetic resonance tomography diagnosis apparatus, as shown and described.

DESCRIPTION

FIG. 1 is a front perspective view of a magnetic resonance tomography diagnosis apparatus showing my new design, according to an embodiment thereof;

FIG. 2 is a rear perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof;

FIG. 9 is a sectional view taken along line 9-9 shown in FIG. 3 with internal mechanism being omitted thereof; and,

FIG. 10 is a sectional view taken along line 10-10 shown in FIG. 3 with internal mechanism being omitted thereof.

The broken lines shown in the drawings illustrate portions of the diagnosis apparatus that form no part of the claimed design.
